US00D927888S

(12) **United States Design Patent** (10) **Patent No.:** **US D927,888 S**
Yu et al. (45) **Date of Patent:** **** Aug. 17, 2021**

(54) **SLEEPING PAD**

(71) Applicants: **Jun Yu**, Ningbo (CN); **Kuncheng Kang**, Sichuan (CN); **Kunjin Kang**, Suizhou (CN); **Hanwei Li**, Zhejiang (CN)

(72) Inventors: **Jun Yu**, Ningbo (CN); **Kuncheng Kang**, Sichuan (CN); **Kunjin Kang**, Suizhou (CN); **Hanwei Li**, Zhejiang (CN)

(73) Assignees: **Jun Yu**, Zhejiang (CN); **Kuncheng Kang**, Zhejiang (CN); **Kunjin Kang**, Zhejiang (CN); **Hanwei Li**, Zhejiang (CN)

(**) Term: **15 Years**

(21) Appl. No.: **29/717,152**

(22) Filed: **Dec. 16, 2019**

(51) LOC (13) Cl. **06-09**

(52) U.S. Cl.

USPC **D6/604**

(57) **CLAIM**

The ornamental design for a sleeping pad, as shown and described.

DESCRIPTION

FIG. 1 is a front view of a sleeping pad, showing our new design;

FIG. 2 is a top plan view thereof;

FIG. 3 is a bottom plan view thereof;

FIG. 4 is a rear plan view thereof;

FIG. 5 is a left plan view thereof;

FIG. 6 is a right plan view thereof; and,

FIG. 7 is a perspective view thereof.

The broken lines in the drawings depict unclaimed portions of the sleeping pad only and form no part of the claimed design.

1 Claim, 7 Drawing Sheets
